UNITED STATES PATENT OFFICE.

CHARLES O. KEAGY, OF ALTOONA, PENNSYLVANIA, AND JAMES R. CARMER, OF WILMINGTON, DELAWARE.

COLLAPSIBLE STAKE-POCKET.

1,287,335.

Specification of Letters Patent. Patented Dec. 10, 1918.

Application filed December 27, 1917. Serial No. 209,172.

To all whom it may concern:

Be it known that we, CHARLES O. KEAGY, a citizen of the United States, residing at Altoona, Blair county, and State of Pennsylvania, and JAMES R. CARMER, a citizen of the United States, residing at Wilmington, in the county of New Castle and State of Delaware, have invented certain new and useful Improvements in Collapsible Stake-
10 Pockets, of which the following is a specification.

In the drawing:

Figure 1 is a perspective view of our invention applied to a car.
15 Fig. 2 is a front elevation of the same.
Fig. 3 is a sectional view on the line 3—3
Fig. 2 looking in the direction of the arrow.
Fig. 4 is a view similar to Fig. 3 with the loop elevated.
20 Fig. 5 is a view similar to Fig. 4 with a stake in position in the pocket.

The object of our invention is to provide a collapsible stake pocket which may be used inside and outside of a car and of such construction that the loop thereof when in closed position is protected against damage by lading.

A further object of our invention is to provide a collapsible stake pocket wherein the stake holding loop is pivotally mounted and bodily shiftable in its bearing, manually or by a jar incident to the movements of a car to which it is secured, whereby the loop, when empty, is free to be shifted and gravitate to a vertical position against the wall of the car, in which position it is not liable to be distorted or otherwise damaged.

A further object of our invention is to provide a collapsible stake pocket having a stop, or stake rest, to limit the downward movement of the stake; and with these and other objects in view our invention consists of the parts and combination of parts as will be hereinafter more fully pointed out.

45 The reference numeral 1 designates the wall of a car.

Our invention comprises a substantially U shaped member which is adapted to be secured to the inner or outer face of a car wall, or to the outer face of the sill. This bracket comprises two side members or brackets 2 and 2^a, and a base member 3, the base member serving as a spacing member for the side brackets, whereby the side brackets are mounted in proper spaced rela-

tion when placed upon a car, the bracket as a whole being secured to a car by means of three rivets or other suitable fastening device 4. By reason of the construction of our bracket member we are enabled to reduce 60 the number of rivets or fastenings 4, which reduction, in one car, is a very material item, both in the cost of the extra rivets and in the cost of applying said rivets. Each side bracket 2 is provided with a bearing 5 near 65 its upper end.

6, is a horizontal abutment projecting from the inner face of the bracket member 2, the lower face of the abutment being substantially in the same plane as the upper 70 face of the bearing 5. The bracket member 2^a is provided with a bearing 7 near its upper end which bearing is extended longitudinally by means of the abutment 8 on the inner face of the bracket member 2^a, 75 the abutment being provided with a recess 9. The upper face of said abutment is inclined as at 10 toward the car wall, as more clearly shown in Fig. 4. The upper face of the spacing member 3 of the bracket is flat and 80 of a substantial area, and constitutes a rest or support upon which the stake 11 rests, said abutment or support constituting a stop to limit the downward movement of the stake in the pocket. The bracket member 2 85 also has an inclined face similar to 10.

12, is a loop having its inner ends formed into journals 12^a and 13 which journals are adapted to be seated in the bearings 5 and 7 of the bracket members as shown in the 90 drawing. Of course the journals 12 and 13 are placed in the bearings 5 and 7 before the pocket is applied to the car.

When the loop 12 is not in use it lies within the outlines of the bracket members as 95 shown in Fig. 3, whereby it is protected against damage or destruction, by the bracket. It has been found that where stake loops are not thus protected they are damaged or destroyed by heavy lading, and by 100 shift of lading. By thus protecting the loop it will be readily understood that the loop is maintained in its original formation and is thus always ready to receive the stake.

We have found it desirable to provide a 105 stop to limit the downward movement of the stake in the pocket and have provided this want by means of the spacing or bottom member 3 which not only functions as a stop for the stake but also functions as a 110

spacing member for the side bracket members 2 and 2^a, thereby insuring the proper spacing of the bracket members when secured to the car.

5 It has been found that the operators frequently leave the loops 12 in the open position shown in Fig. 1 after removing the stake, in which position they are liable to be damaged in the loading of a car, and by 10 shifting loads. We, by our invention insure the return of the loop 12 to the closed position shown in Figs. 2 and 3 automatically. When the loop is left in the open position, just referred to, it lies within the 15 recess 9 and upon the inclined face 10 of the bracket member 2^a, so that any jar to the car or bracket member will cause the loop to bodily shift to the left out of the recess 9 whereupon the loop 12 is free to gravitate 20 to its closed position shown in Figs. 2 and 3 and this movement is accelerated more or less, by reason of the rearwardly inclined cam face 10, which cam face, also more or less, serves to hold the loop in such closed 25 position.

The function of the abutment 6 is to limit the upward movement of the loop 12.

From the above it will be seen that we have provided a collapsible stake pocket in 30 which the loop is adapted to be shifted when empty, either manually or by a jar to closed position, and when in that position is protected by the bracket member against damage. It will also be seen that we have provided means functioning as a spacing element for the side bracket member and also 35 functioning as a stop to limit the downward movement of the stake.

What we claim is:

40 1. In a stake pocket the combination with a substantially U shaped member adapted to be secured to the wall of a car, and a stake embracing element secured at its ends to the sides of the said member, the body of 45 said element being constructed to lie when not in use against the wall of the car and within the U shaped member whereby it is protected against damage.

50 2. A collapsible stake pocket comprising a bearing at each side of the pocket, and means to limit the downward movement of the stake, a loop movably mounted in said

bearings and when empty bodily shiftable in said bearings, manually, or by jar incident to the movement of the car to which it 55 is secured, whereby the loop will be free when shifted to gravitate to a vertical position against the wall of the car, in which position it is not liable to be distorted or otherwise damaged.

60 3. A collapsible stake pocket comprising a substantially U shaped bracket, bearings in the side members of the bracket member, the bottom member of said bracket member functioning as a stop to limit the downward movement of a stake, a loop mounted in the said bearings and adapted to lie when empty within said U-shaped bracket member whereby the loop is protected when in closed position against distortion by lading.

65 4. A stake pocket comprising bracket members adapted for attachment to a car, bearings on said bracket members, an inclined face on one of said bracket members adjacent to the bearings on one of said bracket members, a stake embracing loop revolvably and bodily shiftably mounted in said bearings and adapted to engage said inclined face when bodily shifted, whereby said loop may be shifted bodily by impact 70 and be free to gravitate to a vertical position against the wall of a car, in which position it is not liable to be distorted or otherwise damaged.

75 5. A stake pocket comprising a substantially U-shaped bracket member adapted to be secured to the wall of a car, bearings on the side members of said bracket member, the bottom member of the bracket member acting as a stop to limit the downward movement of a stake, both of said bracket members having an inclined face adjacent both of said bearings, a stake embracing loop revolvably and bodily shiftably mounted in said bearings and adapted to engage said 80 inclined face when bodily shifted, said loop when empty lying within the confines of said U shaped bracket member whereby it is protected against distortion and damage.

90 In testimony whereof we affix our signatures.

CHARLES O. KEAGY.
JAMES R. CARMER.
